TYPE BAR RESTRAINING MECHANISM FOR
ACCOUNTING MACHINESWalter A. Anderson, Trumbull, Conn., assignor to
Underwood Corporation, New York, N. Y., a cor-
poration of Delaware

Application July 25, 1951, Serial No. 238,446

3 Claims. (Cl. 235—60.31)

1

This invention relates to computing and printing machines, and more particularly to a mechanism therefor for controlling the extent of movement of the type bars provided therein during totaling operations of the machine.

Prior machines of the character described usually include devices for supporting a work sheet and a plurality of type bars carrying type for printing amounts on said work sheet. The type bars are mounted for engagement by at least one totalizer for adding, subtracting and totaling amounts, are spring actuated to printing positions, and are restored by means of a common operator. During totaling operation of the machine, the totalizers are disengaged from the type bars immediately following the printing of the total to enable the type bars to be restored to their normal position while the totalizer wheels remain at zero. With the disengagement of the totalizers, the type bars, being spring actuated, are no longer restrained and may jump from the total printing positions to the farthest position allowable from their home position, where they will be stopped by abutting a common stop or by striking the restoring common operator. The shock or jar incident to such stopping of the type bars may be sufficient to disrupt the transfer devices associated with the totalizers, and with resultant inaccurate computations and with undesirable wear and injury to the parts.

Accordingly, one object of the present invention is to provide a mechanism whereby the type bars are held in their total printing positions after the release thereof by the totalizers until the type bars are acted upon and restored to their home positions differentially by the common operator.

It is also an important object of the present invention to provide a mechanism such as described above that is inoperative during adding and subtracting cycles of the machine, and is released to an operative condition and restored to its normally inoperative condition by the machine cycling means only during a total printing cycling of the machine.

An object ancillary to the preceding objects is to provide a type bar movement controlling mechanism that is a unitary assembly simple in construction, which is readily attachable and detachable without disturbing associated parts, and is fast and dependable in operation.

With these and incidental objects in view, the invention consists in certain novel features of construction and combinations of parts, the important elements of which are set forth in appended claims, and a preferred embodiment of

2

which is hereinafter described with reference to the drawings which accompany and form part of the specification.

In the drawings:

5 Figure 1 is a right hand side view of a machine embodying the present invention showing the parts in normal position.

Figure 2 is a perspective view showing the type bar retaining device in normal position,

10 Figure 3 is a right hand side view showing the parts in the position they occupy when the total key is depressed and the machine is at half cycle,

Figure 4 is a sectional view similar to Figure 3 showing the parts released to operative relation

15 with the type bars by the machine cycling means as it traverses the return stroke of the machine cycle,

Figure 5 is a detail perspective view of certain 20 of the parts of Figure 2.

The invention is exemplified herein in connection with an accounting machine similar to the one disclosed in Patent No. 1,946,505, to Oscar J. Sundstrand, dated February 13, 1934, to which patent and machine reference may be had for an understanding of features of construction, and the mode of operation thereof, that are not fully described or illustrated herein.

Referring to Figure 1 of the drawings, a work sheet is supported on a platen 10 rotatably 25 mounted in a traveling paper carriage (not shown). Type bars 11 carrying type 12 are supported for vertical slidable movement on a bar 13 rigid in the machine frame (not shown). Type bars 11 normally are held in their lowered 30 position by means of a common operator 15 acting upon type bar lifts 16 pivoted in the machine frame, and are raised to position the type 12 for printing on a work sheet by means of springs 35 acting upon type bar lifts 16 in the manner disclosed in the above patent. Each of the type bars 11 carries racks 17 and 17a for engagement by totalizers 18 and/or 19 for adding, subtracting, and totaling amounts in the manner disclosed in the patent.

40 The machine includes a main shaft 20 which is connected with a suitable motor, not shown, and, during a machine cycle is rocked first counterclockwise to constitute the forward stroke of the machine cycle, and then returned to its 45 normal position as shown in Figure 1, to constitute the return stroke of the cycle. During the forward stroke of a total taking machine cycle, the common operator 15 is rocked upwardly and away from the type bar lifts 16, enabling the 50 actuating springs (not shown) to rock the type

bar lifts 16 upwardly and, by means of a pin 21 engaging in a slot 14 of type bar 11 to raise the type bars to the total position. Also, during the forward stroke of the machine cycle, the totalizer 18 or 19 remains engaged with racks 17 or 17a, so that as the type bars rise, the totalizer wheels are rotated until one or the other of two lugs provided on each adding wheel abuts transfer devices (not shown) to position type 12 in printing position. Early in the return stroke of the machine cycle, a type aligner 23 is engaged with teeth 24 provided in each type bar 11 to align type 12 in printing position. Hammer trips 25 are then acted upon in the conventional manner to release hammers 26 to strike and imprint type 12 on the work sheet.

Immediately following printing, restoration of hammers 26 is started, and disengagement of the type aligner 23 and teeth 24 in type bars 11 is effected. Before the common operator 15 has restored sufficiently to contact the type bar lift 16 occupying the farthest position from home position, totalizer 18 or 19 is disengaged from racks 17 or 17a, leaving each type bar 11 free to jump upwardly until the associated type bar lift 16 meets and strikes the common operator 15 with a resultant undesirable shock.

The present invention provides means for preventing such undesirable jumping of type bars 11. Such preventing mechanism includes a pair of plates 28 each secured to one of the side plates 29 supporting totalizers 18 and 19, said plates 28 being rigidly connected by a shaft 31. Pivoted on another shaft 32 also rigid in plates 28 is a cradle 34, shaft 32 also having pivoted thereon a plurality of pawls 35, one for each type bar 11, and normally tensioned by means of springs 37 connected between pawls 35 and shaft 31 to bear against a shaft 38 rigid in cradle 34. Secured to the lower end of each type bar 11 is a plate 40 provided with teeth for engagement by pawls 35. During a normal adding or subtracting operation of the machine, pawls 35 should be held in the normal position where they are clear of the teeth in the plates 40. For this purpose, a latching lever 43 is pivoted on a stud 44 securing plate 28 to plate 29 and is provided with a shoulder 46 normally held to the rear of a square stud 47 fixed in cradle 34. A lever 49, Figure 1, is yieldably connected by means of a spring 50 to latch lever 43, lever 49 being fixed on the standard total signal control lever 52 of the machine and pivoted therewith on a shaft 53 fixed in the machine frame. The forward end of lever 52 lies under an ear 56 forming part of a plate 58 fixed on the total key 59. The total key 59 is mounted for vertical slidable movement in a keyboard frame 61 and is tensioned to a normally raised position by means of a spring 62. With total key 59 in its normally raised position, Figure 1, lever 49 is free to press downwardly on the forward end of latching lever 43, to hold shoulder 46 in position to engage the square stud 47.

Cradle 34 is returned to the Figure 1 position in which lever 43 may drop its shoulder behind stud 47 at the end of each machine cycle. For such purpose, a bracket 65 having an upstanding leg 67 is fixed on the cradle 34. Fixed on the main shaft 20 is a plate 68 carrying a pin 70 which at the completion of the return stroke of the machine cycle, strikes leg 67 and rocks cradle 34 about pivot 32 to retract pawls 35 clear of plates 40 on type bars 11, by means of shaft 38 and to shift stud 47 in front of shoulder 46.

Conditioning of the machine for totaling is

usually effected by the depression of total key 59 before cycling the machine. It can, however, be readily seen that the engagement of pawls 35 with the teeth in plates 40 should not be effected until after type bars 11 have become located in their total printing positions as controlled by totalizer 18 or 19. The present invention provides means whereby the machine may be conditioned for totaling by depression of key 59, while pawls 35 are restrained from engaging with the teeth of plates 40 until immediately prior to the printing of the total. To restrain pawls 35, a pawl 71 and stop 73 are pivoted on a stud 74 rigid in an upwardly extending arm 76 forming part of bracket 65 and including a spring supporting ear 77. Stop 73 also is provided with a spring supporting ear 79 and, with stop 73 pivoted on stud 74, a spring 80 stretched between ears 77 and 79 normally tensions ear 79 to rest against the rear edge of the upwardly extending arm 76. Stop 73 is provided with a second spring supporting ear 83 extending therefrom in the opposite direction to that of ear 79. Pawl 71 is similarly provided with a spring supporting ear 85, see Figure 5, and a spring 86 stretched between ears 83 and 85 tensions pawl 71 to normally rest with its rear edge against ear 83 of stop 73.

A short stud 91 in plate 68 during the forward machine cycle passes idly by pawl 71 but rocks pawl 71 and stop 73 at the start of the return half of the machine cycle to shift stop 73 above a stop 89 fixed in the frame, as shown in Figure 4, to release the pawls 35 for engagement with racks 40.

Summary

Upon depression of total key 59 prior to a machine cycle, lever 49 is rocked counterclockwise to raise shoulder 46 of lever 43 above stud 47. Until the beginning of the following machine cycle, however, cradle 34 and pawls 35 are held in their normal position by the engagement of pin 70 with leg 67 of bracket 65. During the forward stroke of the machine cycle pin 70 leaves leg 67, enabling springs 37 to rock pawls 35 and cradle 34 about shaft 32 toward plates 40 on type bars 11. Stop 73 engages with fixed stop 89 during the movement and pawls 35 are arrested in a position just clear of the teeth in plates 40, to enable the free and easy movement of type bars 11 to total printing positions.

During the remaining part of the forward stroke, pin 91 which is shorter than pin 70 but at a greater radius from shaft 20 strikes the lower edge of pawl 71, pivoting the pawl 71 about stud 74 and stretching spring 86 to enable passage of pin 91 past pawl 71.

Upon the start of the return stroke of the machine cycle, the type aligner 23 is moved into engagement with teeth 24 in type bars 11 to align type 12 and shortly thereafter hammers 26 are released by releases 25 to strike and print from type 12. Substantially at the same time pin 91 acts upon the top edge of pawl 71 to pivot the pawl 71 and stop 73 about stud 74, stretch spring 80, and lift stop 73 above the fixed stop 89, enabling springs 37 to further rock cradle 34 and move pawls 35 into engagement with the teeth in plates 40 as shown in Figure 6.

During the next portion of the return stroke, hammers 26 are restored, type aligner 23 is moved from engagement with teeth 24 in type bar 11, and totalizer 18 or 19 is moved from engagement with racks 17 or 17a, leaving type bars 11 completely under the control of pawls 35, which pre-

vent movement of the type bars beyond their total printing positions. As type bars 11 are restored to their normally lowered position by means of the common operator 15, the pawls 35 ratchet over the teeth in plates 40. Also, during the return stroke, the total key 59 is released to its normally raised position, leaving latching lever 43 resting on the top surface of square stud 47, and in condition for reengagement of its shoulder 46 in back of the square stud 47 holding pawls 35 clear of the teeth in plates 40. The engagement of pin 70 and leg 67 at the completion of the machine cycle in the manner hereinbefore described restores cradle 34 to its Figure 1 position and retains it there.

The above description is of a preferred embodiment only of my invention and is not to be taken in a limiting sense since many variations are possible without departure from the features of the invention, all coming within the scope of the following claims.

What is claimed is:

1. In a machine of the class described having a power means, a plurality of actuators resiliently advanceable from and power restored to a home position, and a register engageable with said actuators to differentially limit movement of said actuators from home position and disengageable from said actuators to permit their power return, the combination of means to prevent advancing movement of said actuators upon disengagement of said register therefrom, said means including actuator engaging detents, and a member common to said detents to hold them from engagement with said actuators, a first latch to hold said preventing means in an ineffective position, a function control member operable to release said latch, a second latch to hold said preventing means ineffective when said first latch is released, a cyclically operated releasing mechanism for said second latch and a connection from said power means to said member and said detents common to said detents to restore said member to and hold them in the disengaged position at the end of a machine cycle.

2. In a machine of the class described having a cyclically operable power means, a register, a plurality of actuators with which said register is engageable to control the extent of advance movement of said actuators and a function control key to control engagement of said register with said actuators, the combination of notched stop member on said actuators, detents yieldingly

urged into engagement with said stop members to prevent advance movement of said actuators, a common member to restrain said detents in a nonengaging position, a latch on said common member, a linkage operable by said function control key to release said latch upon depression of said key, a restoring means operated by said cyclic power means to restore said common member and said detents to a home position and to free said common member and said detents for movement to an effective position at the start of each machine cycle, a second latch to restrain said common member when released by said first latch and cyclically operated releasing means for said second latch.

3. In an accounting machine of the class described having a cyclically operating power means, a plurality of type bearing bars, a power operated restoring bar to free said type bars for resilient advance from and to restore said type bars to a home position, a register engageable with said type bars to limit their free movement from home position and disengageable therefrom prior to the beginning of restoration of said type bars, leaving said bars free to make a further advance movement, a stop member connected to each type bar, a detent urged into engagement with each said stop member to prevent movement of said type bar from home position, the combination of a member common to said detents to restrain them from movement into engagement with said stop members, an arm connected to said power means to free said common member during a machine cycle, a latch for said common member to arrest said common member when freed by said arm, a function control member, means operated by said member upon operation thereof to release said latch, a second latch to arrest said common member prior to engagement of said detents with said stop members, and means on said arm to release said second latch after arrest of said type bars under control of said register and prior to the disengagement of said register from said type bars.
